FORK OR THE LIKE

Marion Anderson Noyes, West Newbury, Mass.,
assignor to Towle Manufacturing Company,
Newburyport, Mass., a corporation of Massa-
chusetts

Application September 12, 1952, Serial No. 21,437

Term of patent 14 years

(Cl. D54—12)

To all whom it may concern:

Be it known that I, Marion Anderson Noyes, a citizen of the United States of America, residing at West Newbury, county of Essex, and Commonwealth of Massachusetts, have invented a new, original, and ornamental Design for a Fork or the like, of which the following is a specification, reference being had to the accompanying drawing, forming a part thereof.

Fig. 1 is a plan view of a fork showing my new design;

Fig. 2 is a side view of the fork shown in Fig. 1;

Fig. 3 is a vertical section taken on the line 3—3 of Fig. 1;

Fig. 4 is a vertical section taken on the line 4—4 of Fig. 1; and

Fig. 5 is a vertical section taken on the line 5—5 of Fig. 1.

While the design is illustrated applied to a fork, it is to be understood that the design may be

used on knives, spoons, or like articles without departing from the spirit of the invention.

I claim:

The ornamental design for a fork or the like, substantially as shown and described.

MARION ANDERSON NOYES.
